UNITED STATES PATENT OFFICE

ERNST OSCAR NEBEL, OF PHILADELPHIA, PENNSYLVANIA

YARN MOISTENING DEVICE

Application filed October 17, 1928. Serial No. 313,100.

This invention relates to a device for moistening yarn as it passes from the cone to the knitting needles of the knitting machine, or which can be used at any place where it is desired to moisten a thread prior to its undergoing some subsequent operation.

The object of the invention is to produce a device which will at all times cause the thread to be entirely submerged in the moistening fluid regardless of the depth of the fluid in the container.

The construction of the device will be fully described hereinafter, reference being had to the accompanying drawings, of which:

Fig. 1 is a plan view;

Fig. 2 is a transverse sectional elevation taken on the line 2—2, Fig. 1, and

Fig. 3 is a longitudinal sectional elevation taken on the line 3—3 of Fig. 1.

The device comprises a container 1 consisting of a bottom 2, end walls 3, 3 and side walls 4, 4 which project above the end walls 3, as clearly shown in Figs. 2 and 3.

Superimposed on the container 1 is a suitable framework 5 comprising longitudinally extending members 6, 6 which rest on the end walls 3, 3 of the container 1, as clearly shown in Fig. 3. The longitudinal members are connected by transversely extending

members 7 and 8 respectively. The frame 5 is also provided with vertically extending angle members 9, 9 which form guides for a suitable float 10. The float 10 comprises a pair of spaced oblong cup members 11, 11 which, in the present instance, are open at the top, as illustrated clearly in Fig. 2. The cup members 11, 11 are connected by a bridge element 12 which is provided with grooves 13, 13 which fit over the upper edge of one of the

side walls of each of the cup members 11 as shown in Fig. 2, set screws 14, 14 being provided in the depending portions 15, 15 and adapted to engage the side walls of the cups 11 which lie within the grooves 13, 13 of the bridge element 12, whereby the said cups are rigidly held in fixed relation with respect to each other.

Intermediate the cups 11, 11 the bridge member 12 is provided with a vertically extending opening 16 in which is mounted the

shank 17 of an eye member 18 which projects below the bottom of the cup members 11, as shown in Figs. 2 and 3. The shank 17 is adjustably secured in the bridge member 12 by means of a set screw 19, whereby the relative position of the eye 18 with respect to the cup members 11, 11 may be regulated as desired. Located within the eye member 18 is a porcelain bushing 20. Located in the transverse members 7 and 8 of the frame 5 are respectively located porcelain bushings 21 and 22.

As shown in Figs. 1 and 3, the transverse member 7 is adapted to be located directly above one of the end walls 3 of the container 1, and the transverse member 8 is spaced inwardly from the opposite end wall 3 of the container for purposes hereinafter set forth. Adjacent the transverse member 7 the longitudinal members 6, 6 of the frame 5 are provided with depending lugs 24 which engage the inside of the end wall 3 of the container. Immediately adjacent the depending lugs 24 and extending outside the said wall of the container the longitudinal members are provided with depending lugs 25, 25 through which extend set screws 26, 26, the ends of which engage the outside of the end wall of the container clamping the same against the depending lugs 24 on the inside 75

of the container, thus the frame 5 is held against relative movement with respect to the container 1. The opposite end of each of the longitudinal members 6 of the frame 5 is provided with a downwardly projecting lug 27 which engages the outside of the adjacent wall of the container as illustrated in Fig. 3. The container is adapted to hold a supply of suitable moistening fluid which may be water, oil, or any of the other well known fluids used for moistening yarn. The thread to be moistened passes longitudinally of the container through the porcelain bushing 21 carried by the transverse member 7, thence downwardly through the fluid α passing through the porcelain eye 20 carried by the float 10, and then upwardly through the fluid passing out through the porcelain bushing 22 in the transverse member 8 of the frame 5. The porcelain bushing 20 is adapt- 100

ed to be set at a predetermined distance below the bottom of the float 10 so that a thread passing through the eye will be submerged in the fluid to a predetermined depth which is maintained uniformly irrespective of the depth of the fluid α in the container due to the float 10 rising and falling as the depth of the fluid is changed.

As above noted the position of the eye 20 with respect to the float 10 may be readily changed by adjusting the shank 17 in the bridge member 12. The porcelain bushings 21 and 22 are held in the transverse members 7 and 8 respectively by set screws 28, 28. The construction above described provides a very efficient and inexpensive device for moistening yarn.

The transverse member 8 with its porcelain eye or thread guide 22 are located inwardly from the end wall 3 of the container 1 over which the thread passes in leaving the moistening device, thus as the thread passes through the thread guide 22 the surplus moistening fluid, carried up by the thread, is removed therefrom as the thread passes into the porcelain bushing 22, dropping back into the fluid in the container, and in this way preventing the fluid from dropping outside the container.

I claim:

1. In a yarn moistening device, the combination of a container for a moistening fluid, said container being open at its top, a framework resting on the top edges of the walls of the container, guides on said framework extending downwardly into said container, a float positioned intermediate said guides, a thread guide carried by said float below the level of the fluid in the container, and thread guides carried by said frame adjacent oppositely disposed walls of the container.

2. In a yarn moistening device, the combination of a container for a moistening fluid, said container being open at its top, a framework resting on the top edges of the walls of the container, guides on said framework extending downwardly into said container, a float positioned intermediate said guides, a thread guide carried by said float below the level of the fluid in the container, and thread guides carried by said frame adjacent oppositely disposed walls of the container, one of the latter guides being positioned inside the adjacent wall of the container.

3. In a yarn moistening device, the combination of a container for a moistening fluid said container being open at its top, a frame work resting on the top edges of the walls of the container, guides on said framework extending downwardly into said container, a float positioned intermediate said guides, a thread guide carried by said float below the level of the fluid in the container, thread guides carried by said frame adjacent oppositely disposed walls of the container, one

of the latter guides being positioned inside the adjacent wall of the container, and means for securing the said framework against relative movement with respect to the container.

ERNST OSCAR NEBEL.
